R. M. PHILLIPS

Des. 171,265

CHAIR

Filed April 13, 1953

FIG. 1.

FIG. 2.

INVENTOR

Richard M. Phillips

UNITED STATES PATENT OFFICE

171,265

CHAIR

Richard M. Phillips, East Peoria, Ill.

Application April 13, 1953, Serial No. 24,481

Term of patent 14 years

(Cl. D15—8)

To all whom it may concern:

Be it known that I, Richard M. Phillips, a citizen of the United States and a resident of East Peoria, county of Tazewell, State of Illinois, have invented a new, original, and ornamental Design for a Chair, of which the following is a specification, reference being had to the accompanying drawing, forming a part hereof.

Fig. 1 is a front perspective view of a chair embodying my new design; and

Fig. 2 is a side perspective view of the same.

I claim:

The ornamental design for a chair, as shown.

RICHARD M. PHILLIPS.
